AUTOMATIC GRINDING MACHINE

Harry Arter, Worcester, and Warren F. Fraser,
Westboro, Mass., assignors to Arter Grinding
Machine Company, Worcester, Mass., a corpo-
ration of Massachusetts

Application March 25, 1933, Serial No. 662,754

20 Claims. (Cl. 51—95)

This invention relates to automatic grinding machines and is more especially concerned with machines of the general character disclosed in the Arter and Fraser Patent No. 1,888,710, granted November 22, 1932 and assigned to the assignee of the present invention.

The present invention aims to simplify the organization of machines of this general type and to adapt such machines for handling a wider range of work by making relatively simple adjustments.

The nature of the invention will be readily understood from the following description when read in connection with the accompanying drawings, and the novel features will be particularly pointed out in the appended claims.

In the drawings,

Figure 1 is a plan view of those parts of automatic grinding machine with which the present invention is more especially concerned;

Fig. 2 is a side elevation of the mechanism shown in Fig. 1;

Fig. 3 is a view, partly in side elevation and partly in vertical section, illustrating more particularly details of the turret construction and the manner in which it is mounted;

Fig. 4 is an end view of the parts shown in Fig. 2;

Fig. 5 is a vertical, sectional view approximately on the line 5—5, Fig. 3;

Fig. 6 is a vertical, sectional view through the machine;

Fig. 7 is a similar view through one end of the cylinder of the mechanism for reciprocating the turret;

Figs. 8 and 9 are views chiefly in vertical section of certain of the main valves for controlling the operations of the machine;

Fig. 10 is a transverse, vertical, sectional view through the turret and the indexing mechanism therefor;

Fig. 11 is a view similar to Fig. 10 but taken in a different plane for the purpose of illustrating the piston valve associated with the stop pawl for acting on the turret;

Figs. 12 and 13 are sectional and end views, respectively, of the clutch parts which are included in the turret indexing mechanism;

Fig. 14 is a plan view of the valve mechanism directly associated with the turret indexing piston and cylinder;

Fig. 15 is a sectional view of said piston, cylinder and valves; and

Fig. 16 is a diagrammatic view of the fluid pressure system.

General organization

An understanding of the machine illustrated in the drawings will be facilitated by a brief description of its general organization and the functions which it performs. Referring more particularly to Figs. 1 and 2 it will be observed that the machine includes a grinding wheel 2 and a turret 3 carrying a series of chucks or collets 4 for holding articles of work while the grinding wheel 2 acts on them. The machine is adapted more especially for operation on rolls, pins, poppet valves, and similar articles where the grinding operations are to be performed upon the end portion of each article of work. Consequently, a loading mechanism of any suitable type is provided for the purpose of forcing a piece of work into each chuck as it arrives in loading position, an additional mechanism rotates the turret intermittently or indexes it to move the chuck successively through their different positions, including particularly the loading and working positions. Preferably all of the movements of the turret are performed hydraulically or through some other type of fluid actuated mechanism. Preferably, also, the chucks are similarly operated. The indexing operation involves not only the rotative movement of the turret but the gradual arresting of that movement without undue jar or strain on the parts and the locking of the turret in its indexed position. At the beginning of the grinding operation on each piece of work the wheel 2 is moved toward the chuck located in working position and at the completion of this movement it remains stationary, except for its rotary motion, while the entire turret is moved in a direction parallel to the axis of the grinding wheel to traverse the work across the face of the wheel.

Wheel head structure and operating mechanism therefor

The grinding wheel 2 is mounted in suitable bearings carried by a wheel slide 5, Fig. 1, the shaft 6 of the wheel being belt connected or driven in any other way from a suitable source of power. For the purpose of giving the wheel the movements above described toward and from the work, the slide 5 is mounted to reciprocate in the frame of the machine and an operating mechanism substantially like that shown in the Fraser Patent No. 1,873,751, granted August 23, 1932, is provided. This mechanism is operated

by a cam 17, Fig. 6, on the cam shaft 18, both of these parts corresponding to those designated by the same numerals in the patent just mentioned. This operating mechanism is so designed 5 that it moves the wheel 2 in rapidly toward the work during the first part of the approaching movement, then completes this movement very gradually, and finally moves the wheel quickly away from the work again when the grinding out 10 operation has been completed.

Turret indexing mechanism

The turret 3 is mounted in suitable bearings 15 to revolve around a horizontal axis and it carries the four equally spaced chucks 4 previously mentioned. For the purpose of producing the indexing movement it is encircled by a worm wheel 8, Fig. 10, secured rigidly thereto and arranged to be driven by a worm 9 keyed on a horizontal shaft 10 which extends under the turret 20 transversely thereto. At one end this shaft carries a pinion 12 which meshes with a gear 13 fast on the end of a horizontal shaft 14. At predetermined times in each cycle of operations of 25 the machine this shaft is revolved by a fluid actuating mechanism best shown in Figs. 10 and 15. It comprises a trunk piston 15 mounted to reciprocate horizontally in the bore of a cylinder block 16. At one side this piston is cut 30 away and has a rack 15' secured to it which meshes with and drives a pinion 19 which is secured to, or is made integral with, a hollow shaft 20 through which the shaft 14 extends.

In order to control the driving connection 35 between the piston and the turret, a clutch, which is indicated in general at 21, is interposed between the two shafts 14 and 20. It consists, as best shown in Figs. 12 and 13, of a flange 22 rigid with the shaft 20 and provided with two 40 lugs 23 projecting axially therefrom and adapted to enter slots 24 formed in a circular flange 25 which projects axially from the right-hand face of the gear 13. Due to this construction the clutch can be engaged in one position only 45 of the two shafts. A spring 26, Fig. 10, acts on the shaft 14 in a direction tending to slide it toward the right, Fig. 10, and thus to hold the clutch parts in operative engagement with each other, in which condition the gear 13 will be 50 connected positively with the hollow shaft 20 and pinion 19.

The movements of the trunk piston 15 are controlled by a main valve mechanism operated by cams on the cam shaft 18, previously referred to, 55 and which presently will be described more in detail, but the clutch 21 is controlled by a secondary or auxiliary valve under the control of one of the main valves and indicated in general at D. This valve is of the piston type and the 60 piston rod 27 is extended, as shown in Fig. 10, and arranged to operate a bell crank lever 28, the lower end of which is forked to straddle a collar 30 secured on the end of the shaft 14, two pins or rolls carried by the lever entering 65 the groove in the collar. The movement of the trunk piston 15 in one direction only is utilized to index the turret, its movement in the opposite direction being simply an idle return movement preparatory to performing the next indexing operation. The main control valve which 70 governs the movements of this piston is so connected with the secondary valve D that it controls its operations also and its movements are so timed that it disengages the clutch at the 75 completion of the indexing movement and causes

it to re-engage again at the beginning of the next indexing movement, the idle return stroke of the piston taking place in the meantime. The mechanism just described is so timed that one complete revolution of the gear 13 completes an indexing movement of the turret, or, in other words, moves the turret through an angle of 90°.

As above stated, it is necessary to bring the turret to a stop in a definite position at the end 10 of each indexing movement, and for this purpose a stop pawl 31, Figs. 10 and 11, is provided and is arranged to enter any one of four recesses or notches 32 formed in a cam ring 33 which encircles the turret and is secured rigidly thereto. 15 This pawl is fulcrumed on a lug projecting from the cylinder block 16 and is connected by a link 34 to a lever 35. A spring 36 acts on this link to hold the pawl in its turret locking position. It may be moved out of this position, however, by 20 means of a piston valve, indicated in general at E, which is under the control of one of the main valves operated by a cam on the main cam shaft 18. It will be evident from an inspection of Fig. 11 that if fluid under pressure is delivered to the 25 left-hand end of the cylinder E it will force the piston to the right, thus operating through the connections just described to swing the pawl out of the notch 32 in which it is located, leaving the turret free to be rotated by the indexing 30 mechanism. This action occurs immediately prior to the commencement of each indexing movement.

Control mechanism

As above stated, the primary control of the 35 various functions of the machine is effected through the cam shaft 18. In addition to carrying the cam 17, this shaft also carries three cams 37, 38 and 39 adapted to operate, respectively, the three main control valves A, B and C. Each of 40 these valves is of the piston type and includes a cylinder with a slideable piston working in it and a spring for forcing the piston in one direction. As shown in Fig. 9 the piston rod of the 45 valve C is extended through the cylinder head and bears against the end of a lever 41 carrying a roll which runs on the periphery of the cam 39. The cam operated lever thus opposes the action of the spring. Each of the other valves A and 50 B is operated in the same manner. All of these valves are essentially alike except for the arrangement of the ports, such arrangement being determined by the functions required of the respective valves.

Each of the valves D and E is of a similar construction in that it includes a piston which is slideable in a cylinder, controls properly spaced and dimensioned ports, and is normally held 55 against one end of the cylinder by a spring. Each of these valves, however, is arranged to be operated by fluid admitted through one of the main valves to the end of the cylinder opposite to the spring.

The general arrangement of the hydraulic system will be readily understood from an inspection of Fig. 16. This system includes a supply tank 42 for the oil or other fluid used, a pump 43 for taking oil from the tank and forcing it under pressure to the various units of the system, a 60 relief valve 44 which is adjustable to regulate the pressure maintained on the system, and suitable pipe connections for conducting the oil from the pump to the various parts of the system and carrying it back again to the tank. It will be 65 70 75

observed that the main valve A controls the supply of oil to the secondary valve D which, as previously stated, operates the clutch. Through this arrangement the valve A exercises a joint control with the valve D over the starting and stopping of the indexing movement. The main valve B controls the operation of the valve E which, as above stated, operates the pawl 31. Both the valves D and E are connected with the opposite ends of the turret indexing cylinder 16 through suitable piping. The arrangement is such that oil under pressure can be forced into either end of the cylinder, as desired, for the purpose of reciprocating the piston 15, both the inflow of oil and the discharge of the exhaust oil being maintained under control so that the rate of movement of the piston is properly governed. A shunted check valve 45 is included in the connections between the two cylinders D and E to assist in this control.

An important function of the valve E is to throttle or so retard the discharge of oil from the cylinder 16 as the indexing piston approaches the end of its indexing movement, that the turret will be gradually brought to rest. As indicated in Fig. 16, the indexing movement of the piston is toward the right. During this movement the oil discharged from the cylinder 16, flows through the valve E around the neck of the piston and then through the valve D, the piston of which at that time is at the upper limit of its stroke, and back to the supply tank 42. Oil under pressure now flows through the valve D into the left-hand end of the cylinder 16. At this time the pressure ports of the valve A are closed but the valve B is admitting oil to the secondary valve E, thus acting to hold the pawl 31 out of the notch 32. After the indexing movement has started, the valve B is moved to permit the exhaust of the oil from the secondary valve E, but there is no pressure on the piston of this valve at this time tending to reverse it due to the fact that the roll 46 on the end of the pawl 31 is riding on the raised surface of the cam 33. As soon as the indexing movement has proceeded far enough to allow the roll to start down the incline into the next notch 32, the spring 36, Fig. 11, acts both to force the pawl into its notch and also to move the piston 47 in the valve E toward the left, Fig. 11, where it will begin to close the ports 48 through which the oil expelled from the cylinder 16 is being forced. This movement of the valve is under the control of the cam rotating with the turret, and the cam is so designed and the parts are so adjusted that the motion of the turret is decelerated upon the entrance of the roll 46 into the notch 32 at such a rate that it is moving at a very slow speed when it is finally stopped by the pawl.

After the indexing operation has been completed, and prior to the initiation of the next indexing movement, the clutch 21 is disengaged and the piston 15 makes its return stroke. The range of movement of this piston and the points at which its movements terminate may be determined by the adjusting screws threaded through the cylinder heads, as shown in Fig. 15.

Turret reciprocating mechanism

After each indexing movement has been completed the turret is reciprocated bodily to carry the work across the face of the grinding wheel. For this purpose the turret is mounted on a slide 58, Fig. 3, which is supported in suitable ways on the machine base or frame 51, and a fluid actuating mechanism is provided to move the slide 58

backward and forward on said ways. This mechanism comprises a cylinder F, Figs. 6 and 16, mounted on a bracket that is secured rigidly to one side of the machine frame. A piston 53 slides in said cylinder and is secured rigidly to a rod 54 which is fastened to the slide 58 by means of a screwthreaded adjusting mechanism of a well known type arranged to be operated by a hand wheel 55. The flow of fluid to and from the cylinder F is controlled by a valve C arranged to be operated by the cam 39 on the cam shaft 18. It admits oil under pressure, first to one end and then to the other, of the cylinder and thus operates through the connections just described to reciprocate the slide 58 and the turret and other parts mounted thereon.

It is desirable to make the return stroke of the slide 58 take place rapidly while the working or grinding stroke should be made relatively slow. Accordingly, the oil conducting pipe 56, which connects the right-hand end, Fig. 6, of the cylinder F with the main control valve C, is arranged to discharge into a passage 57, Fig. 7, having communication with the cylinder F both through a check valve 58 and also through an adjustable needle valve 59. Consequently, when oil is being forced under pressure through the valve C and pipe 56 to the passage 57, it flows freely past the check valve 58 into the right-hand end of the cylinder F and produces a quick return movement of the piston and slide. An instant later this supply of oil is cut off by the valve C and oil then is admitted through the pipe 61, Fig. 6, to force the piston in the opposite direction. The oil in the right-hand end of the cylinder cannot escape through the check valve and finds an outlet only through the needle valve. Consequently, by properly adjusting this valve the speed of the grinding movement can be varied within relatively wide limits.

It should be noted that all of the parts for operating the turret and the chucks are mounted on the slide 58 so that the entire turret operating mechanism is reciprocated with the turret and the relationship of this mechanism to the turret is not disturbed by the reciprocating movement. It may also be pointed out that both the turret and its supporting and operating mechanism are all mounted on a plate 62, Figs. 1, 3 and 6, which is connected with the slide 58 by a pivot pin 63 and by bolts that extend through slots 64-64, Fig. 1, in the plate 62 and serve to secure this plate in the desired relationship to the slide. This arrangement provides for the angular adjustment of the turret relatively to the grinding wheel to facilitate the grinding of articles of work having tapered or conical ends.

Chuck construction and operation

While chucks of any suitable type can be used in the machine, and the nature of them necessarily will be determined by the requirements of different articles of work, chucks of the general type shown in the Fraser and Arter patent above mentioned are well adapted for use in this machine when it is employed for grinding the ends of rolls, pins, and the like. Each chuck includes an expandable work holder 65, Fig. 3, mounted in a suitable barrel and associated with a slidable plunger 66 that is urged rearwardly by a spring 67. Slidably mounted inside the plunger 66 is an ejector 70 arranged to be operated by a coiled spring 71. This whole chuck body is mounted on roller bearings to revolve rapidly in the chuck barrel 72 that is clamped securely in the turret.

Normally the spring 67 holds the chuck in its open or expanded position, the elements of the work clamp 65 tending to expand due to the inherent resiliency of their supporting parts. For the purpose of closing the chuck a fluid actuated mechanism is provided, comprising a flexible bellows 73 mounted in the hollow body or cylinder 74 which is secured rigidly to the end of the chuck body. When fluid under pressure is admitted to this cylinder it collapses the bellows and moves the plunger 66 forward, thus forcing the externally tapered surfaces of the work holder 65 outwardly in contact with the internally tapered surfaces of the nose pieces 68 of the chuck. This contracts the work holder sufficiently to cause it to clamp an article of work positioned in it. A light coiled spring 75 is interposed between the cylinder 74 and the chuck body to take up constantly any lost motion in the bearings, or, in other words, to keep the roller bearings under a slight load. Obviously the bellows 73 could be replaced by a piston and such a construction is sometimes used.

The pressure actuated mechanism of all four chucks is under the control of a single valve G located at the end of the turret and in axial alignment with the turret. It comprises a spider-like valve body having four arms which are secured to connectors 77 projecting rearwardly from the ends of the cylinders 74, and an oscillating tapered valve plug 76 fitting in a central hole in said body. Oil under pressure is conducted from the pump 43, Fig. 16, through a flexible pipe 78, Fig. 2, to the lower or inlet chamber 80, Fig. 3, of the valve G, while another pipe 81 carries the exhaust oil away from the outlet chamber 82.

In this machine the loading mechanism is arranged to force an article of work into each chuck as it arrives in the position indicated at 4' in Figs. 1 and 5. It will be seen from an inspection of these figures that the inlet and outlet chambers in the valve G are so positioned as to maintain pressure normally on the chuck which is in grinding or working position and also on that immediately following it, but that no pressure is maintained on either the chuck in loading position or on the uppermost chuck shown in these two figures. Immediately after a piece has been loaded into the chuck 4' the indexing movement starts and it carries the piece of work just forced into the chuck away from the loader and behind a guard 83, Fig. 1, which prevents the ejector plunger 78 from forcing the article out of the chuck. At the end of the guard 83 is a positioning roller 84 into contact with which the end of the work is carried immediately after leaving the guard and which serves to force the work backwardly so that its end projects into a fixed and predetermined position. This action occurs approximately as the chuck arrives at the end of an indexing movement. At the end of the indexing operation the valve plug 76 is rotated backwardly far enough to apply pressure to the chuck in which the work has just been positioned by the roll 84, and later, during the indexing operation, it is swung forward again, i. e., with the direction of rotation of the turret, in order to clamp this piece of work securely and also to release the finished piece of work held in the lowermost chuck. Fig. 5 shows the valve plug in the position which it occupies at the end of the indexing movement and just before beginning its backward swing.

For the purpose of operating the valve in this manner and in timed relationship to the indexing movement, the valve plug 76 is connected by a

link 85, Figs. 1 and 2, with an arm 86 secured rigidly on the rock shaft 87. Another arm 88 also secured to this rock shaft carries a roll running in the groove of a cam 89 which is secured fast on the hollow shaft 28 that is revolved directly by the trunk piston 15. Since this piston produces the indexing movement, the timing of the operation of the valve G with reference to said movement can be made very accurate by the arrangement just described.

It will be observed that since the movement of the valve 76 in a clockwise direction, Fig. 5, is coincident with the indexing movement of the turret, the port 80 in said valve will move in such a manner that pressure will always be maintained upon a chuck holding an article of work during the entire period in which said chuck travels from the grinding position to the discharging position. In fact, the work is not released until the valve 76 is rocked in a counter-clockwise direction, Figs. 2 and 5, following the completion of the indexing stroke. Upon the backward or counter-clockwise movement of the valve 76 the discharge port 82 is brought into communication with the port leading to the chuck then in discharging position and thus relieves the pressure on the bellows 73, permitting the spring 67 to open the chuck and release the work. The ejector 10 immediately forces the work out of the chuck so that it is empty when it arrives at the loading station. Thus any possibility of discharging the work while it is within the zone of operation of the grinding wheel is prevented, and its discharge is permitted only after the chuck has arrived at the extreme lowermost position of its range of movement.

For the purpose of revolving each chuck while it is in its working position the cylinder 74 of each chuck is grooved to engage a series of V-shaped belts 91, Figs. 1, 2 and 3, all driven by an electric motor 92 which is supported on one corner of the plate 62. A belt tightening idler 93 maintains a substantially uniform tension on all of the belts. The arrangement is such, as will be evident from an inspection of Fig. 2, that each chuck is revolved rapidly while it is in working position but passes out of engagement with the belts before it arrives in its loading position so that it is not driven at this time.

In this machine the loading operation may conveniently be performed hydraulically, and a cylinder H, Fig. 16, is provided for this purpose, this cylinder being connected with one of the main control valves A which, as above stated, is the valve that operates the turret clutch, Figs. 12 and 13. Any suitable mechanism may be provided for delivering the work to the loader, such, for example, as the chute 94, Fig. 1. Usually the loading operation consists simply in forcing an article of work endwise into the open chuck 60 against the pressure of the ejector.

The hydraulic system is subject to fluctuations in pressure due to sudden demands placed upon it, and in order to avoid any possibility of having the work ejected from the chucks because of some sudden but temporary drop in fluid pressure, the supply pipe leading to the valve G is equipped with a check valve 95, Fig. 16, which prevents reverse flow of the fluid through this supply line, and a pressure stabilizing or compensating device 96 is connected to the line between this check valve and the valve G. This device may consist simply of a cylinder with a spring pressed piston mounted in it, the spring being fully compressed when the pressure is normal, but expanding and

forcing the piston forward immediately when any drop in pressure occurs. The cylinder holds a considerable body of oil so that it will serve to maintain pressure on the chucks for a substantial 5 interval of time during which sub-normal pressure may exist in other parts of the system.

Operation

The operation of the machine and the relative 10 timing of the functions of its various units have been so completely set forth in connection with the foregoing description of construction that no further statement of operation is believed to be necessary. It will be evident, however, that the 15 invention provides an automatic grinding machine capable of handling a great variety of work and which is extremely positive, fast, and reliable in operation while at the same time being relatively simple in construction. The fact that the 20 changes in adjustments required for the handling of work of different sizes and dimensions can be made very quickly and easily is a very important practical advantage. The machine also lends itself readily to re-tooling to adapt it for different 25 articles of work.

While we have herein shown and described a preferred embodiment of our invention, it will be understood that this disclosure has been made rather by way of illustration than limitation and 30 that the invention is susceptible of embodiment in other forms without departing from the spirit or scope thereof.

Having thus described our invention, what we 35 desire to claim as new is:

1. In a grinding machine, the combination of 40 a turret carrying a series of work supporting chucks, a grinding wheel for acting on the work supported in said chucks, means for indexing said turret to bring said chucks successively into working and loading positions, fluid actuated mechanism for operating said chucks, and controlling means for said mechanism operative to cause the chuck leaving the working position to remain closed and to close the chuck approaching said 45 position while leaving the chuck at the loading position open.

2. In a grinding machine, the combination of 50 a turret carrying a series of work supporting chucks, a grinding wheel for acting on the work supported in said chucks, fluid actuated mechanism for indexing said turret to bring said chucks successively into loading and working positions, a fluid actuated operating mechanism associated with each individual chuck for controlling the 55 clamping and releasing of the work, an oscillating valve common to all of said fluid actuated chuck operating mechanisms for controlling their operation, and means for oscillating said valve during the indexing movement, and subsequently returning said valve to its normal position again 60 preparatory to the next indexing movement.

3. In a grinding machine, the combination of 65 a turret carrying a series of work supporting chucks, a grinding wheel for acting on the work supported in said chucks, fluid actuated mechanism for indexing said turret to bring said chucks successively into loading and working positions, a fluid actuated operating mechanism associated with 70 each individual chuck for controlling the clamping and releasing of the work, an oscillating valve common to all of said fluid actuated chuck operating mechanisms for controlling their operation, and connections between said valve and said indexing mechanism for oscillating the valve in a 75

definite timed relationship to the indexing movements of the turret.

4. In a grinding machine, the combination of a 10 turret carrying a series of work supporting chucks, a grinding wheel for acting on the work supported in said chucks, fluid actuated mechanism for indexing said turret to bring said chucks successively into loading and working positions, a fluid actuated operating mechanism associated with each individual chuck for controlling the clamping and releasing of the work, an oscillating valve common to all of said fluid actuated chuck operating mechanisms for controlling their operation, a slide on which said turret is mounted, means supporting said slide for reciprocating movement, fluid actuated mechanism for reciprocating said slide, and controlling means for automatically effecting the operation of all of said fluid actuating mechanisms in definite timed relationship to each other. 15

5. In a grinding machine, the combination of a 20 turret carrying a series of work supporting chucks, a grinding wheel for acting on the work supported in said chucks, fluid actuated mechanism for indexing said turret to bring said chucks successively into loading and working positions, a fluid actuated operating mechanism associated with each individual chuck for controlling the clamping and releasing of the work, an oscillating valve common to all of said fluid actuated chuck operating mechanisms for controlling their operation, a slide on which said turret, together 25 with said fluid actuated mechanisms and said valve are mounted, means supporting said slide for reciprocating movement, fluid actuated mechanism for reciprocating said slide, and controlling means for automatically effecting the operation of all of said fluid actuating mechanisms in definite timed relationship to each other. 30

6. In a grinding machine, the combination of a 35 grinding wheel; means for driving said wheel; a turret carrying a plurality of chucks each adapted to support a piece of work for the operation thereon of said wheel; fluid actuated mechanism for indexing said turret to carry the chucks successively 40 into different operative positions including a working position and a loading position; said mechanism comprising a cylinder, a piston working therein, means for transmitting the movements of said piston to said turret to rotate the 45 turret intermittently; fluid operated valve means for controlling the admission of fluid under pressure to said cylinder and the escape of fluid therefrom, and a primary controlling mechanism for operating said valve means. 50

7. A machine according to preceding claim 6 55 including a clutch controlling the operative connection between said piston and said turret, and means under the control of said primary controlling mechanism for operating said clutch at predetermined points in each cycle of operations of the machine. 60

8. In a grinding machine, the combination of 65 a grinding wheel; means for driving said wheel; a turret carrying a plurality of chucks each adapted to support a piece of work for the operation thereon of said wheel; fluid actuated mechanism for indexing said turret to carry the chucks successively 70 into different operative positions including a working position and a loading position; said mechanism comprising a cylinder, a piston working therein, a shaft arranged to be revolved by the movement of said piston, a worm carried by said shaft, and a worm wheel revolving with said turret and driven by said worm; and 75

valve mechanism operated in timed relationship to other operations of the machine for controlling the rate of movement of said piston in said cylinder.

5 9. In a grinding machine, the combination of a grinding wheel; means for driving said wheel; a turret carrying a plurality of chucks each adapted to support a piece of work for the operation thereon of said wheel; fluid actuated mechanism for indexing said turret to carry the chucks successively into different operative positions including a working position and a loading position; said mechanism comprising a cylinder, a piston working therein, means for transmitting the movements of said piston to said turret to rotate the turret intermittently; a main valve mechanism for controlling the rate of movement of said piston in said cylinder; a stop device for locking said turret in its indexed position, and fluid pressure actuated means connected with said stop device to operate it, the last mentioned means comprising a secondary valve under the control of said main valve mechanism and cooperating with it and with said stop device to decelerate the movement of the turret and to bring the turret gradually to a stop at the end of its indexing movement.

10 10. In a grinding machine, the combination of a grinding wheel; means for driving said wheel; a turret carrying a plurality of chucks each adapted to support a piece of work for the operation thereon of said wheel; fluid actuated mechanism for indexing said turret to carry the chucks successively into different operative positions including a working position and a loading position; said mechanism comprising a cylinder, a piston working therein, means for transmitting the movements of said piston to said turret to rotate the turret intermittently, and a clutch for controlling the operative connection between said piston and said turret; fluid actuated mechanism for operating said clutch; and means for controlling the operations of said fluid pressure actuated mechanisms in timed relationship to each other and to cause said clutch to transmit the movements of said piston in one direction only to said turret, said controlling means including cam operated main valves and fluid operated secondary valves under the control of said main valves, co-operating both to control the direction of movement of said piston and also to bring the piston gradually to rest at the end of its indexing stroke.

15 11. In a grinding machine, the combination of a turret carrying a series of work supporting chucks, a grinding wheel for acting on the work supported in said chucks, fluid actuated mechanism for indexing said turret to bring said chucks successively into loading and working positions, a fluid actuated operating mechanism associated with each individual chuck for controlling the clamping and releasing of the work, an oscillating valve located at the end of the turret and common to all of the latter fluid actuating mechanisms for controlling their operations, said valve being constructed to normally maintain the chuck in working position closed and that in loading position open, mechanism for automatically oscillating said valve in timed relationship to each indexing movement of the turret to hold the chuck in working position closed while it swings away from the latter position but to open it when it reaches a discharging point, and to close each chuck into which work has just been loaded before the latter chuck arrives in working position.

20 12. A machine according to preceding claim 11

in which the connections for transmitting movement from said piston to said turret includes a clutch, and a fluid actuated mechanism under the control of said valve mechanism for operating said clutch at approximately the beginning and the end of each indexing movement.

25 13. In a grinding machine, the combination of a grinding wheel; a turret carrying a plurality of chucks each adapted to support a piece of work for the operation thereon of said wheel; fluid actuated mechanism for indexing said turret to carry the chucks successively into different operative positions including a working position and a loading position; a stop pawl cooperating with said turret to arrest the movement of the turret at the end of each indexing operation; a piston valve for operating said pawl; a main valve mechanism for controlling said indexing operation and the operation of said piston valve, said turret having a plurality of cam elements thereon for engaging said pawl; and connections between said pawl and said piston valve for operating the latter valve to cause it to exercise a control over the operation of said fluid actuated mechanism.

30 14. In a grinding machine, the combination of a grinding wheel; a turret carrying a plurality of chucks each adapted to support a piece of work for the operation thereon of said wheel; fluid actuated mechanism for indexing said turret to carry the chucks successively into different operative positions including a working position and a loading position; each of said chucks including relatively movable jaws for gripping the work, a spring normally serving to hold said chuck open and parts arranged to be actuated by fluid pressure for closing said chuck; means in the turret for supporting said chucks for independent rotation about axes parallel to each other and to the axis of rotation of the turret; a valve mounted at the end of said turret to swing about the axis of the turret; and connections for causing said valve to control the flow of fluid under pressure to said chucks to operate them at the desired times.

35 15. In a grinding machine, the combination of a turret carrying a plurality of work supporting chucks, a grinding wheel for acting on the articles of work supported in said chucks, and fluid actuated mechanism for indexing said turret to bring said chucks successively into grinding position, said mechanism being constructed and arranged to move said turret rapidly during a portion of each indexing movement and including means under the control of the turret for decelerating the motion of the turret to bring it gradually to a stop at the end of said indexing movement.

40 16. In a grinding machine, the combination of a turret carrying a series of work supporting chucks, a grinding wheel for acting on the work supported in said chucks, fluid actuated mechanism for indexing said turret to bring said chucks successively into loading and working positions, a fluid actuated operating mechanism associated with each individual chuck for controlling the clamping and releasing of the work, a valve common to all of said fluid actuating mechanisms for controlling their operation, mechanism for operating said valve in timed relationship to the other operations of the machine, a single source of supply for delivering fluid under pressure for operating said means and said mechanisms, and means for maintaining the pressure of the fluid supplied to said chuck operating mechanisms ap-

proximately unaffected by a temporary drop in the pressure in the main fluid supply system.

17. In a grinding machine, the combination of a grinding wheel; means for driving said wheel, a turret carrying a plurality of chucks each adapted to support a piece of work for the operation thereon of said wheel; fluid actuated mechanism for indexing said turret to carry the chucks successively into different operative positions including a working position and a loading position; said mechanism comprising a cylinder, a piston working therein, and means for transmitting the movements of said piston to said turret to rotate the turret intermittently; valve means for controlling the admission of fluid under pressure to said cylinder and the escape of fluid therefrom, mechanism for operating said valve means, a clutch controlling the operative connection between said piston and said turret, and an auxiliary cylinder and piston under the control of said valve means for operating said clutch.

18. In a grinding machine, the combination of a grinding wheel; means for driving said wheel, a turret carrying a plurality of chucks each adapted to support a piece of work for the operation thereon of said wheel; fluid actuated mechanism for indexing said turret to carry the chucks successively into different operative positions including a working position and a loading position; said mechanism comprising a cylinder, a piston working therein, and means for transmitting the movements of said piston to said turret to rotate the turret intermittently; valve means for controlling the admission of fluid under pressure to said cylinder and the escape of fluid therefrom, mechanism for operating said valve means, and a cam secured to and revolv-

ing with the turret and cooperating with said valve means to so control the flow of the actuating fluid that the turret will be brought to rest gradually at the end of each indexing movement.

19. In a grinding machine, the combination of a turret carrying a series of work supporting chucks, a grinding wheel for acting on the work supported in said chucks, mechanism for indexing said turret to bring said chucks successively into loading and working positions, a fluid actuated operating mechanism associated with each individual chuck for controlling the clamping and releasing of the work, a valve comprising a valve body rigid with said turret and having ports communicating with said respective chuck operating mechanisms, said valve also including a valve plug around which said valve body is rotatable, and connections between said valve plug and said indexing mechanism for oscillating the plug in a definite timed relationship to the indexing movements of the turret.

20. In a grinding machine, the combination of a turret, a plurality of work supporting chucks mounted in said turret for rotation about their respective axes, a grinding wheel for acting successively on the articles of work supported in said chucks, fluid actuated mechanism for indexing said turret to bring said chucks successively into grinding and loading positions, mechanism for operating said chucks to cause them to grip and release the work at the desired times in the cycle of operations of the machine, and mechanism for relatively moving said grinding wheel and said turret to produce a traversing movement of the wheel on the work in a direction transversely to the axes of rotation of the respective chucks.
